UNITED STATES PATENT OFFICE.

FREDERICK W. WALKER, OF ROYAL OAK, MICHIGAN, ASSIGNOR TO PACKARD MOTOR CAR COMPANY, OF DETROIT, MICHIGAN, A CORPORATION OF MICHIGAN.

DESIGN FOR A HANDLE.

61,057.

Specification for Design.

Patented June 6, 1922.

Application filed October 8, 1920. Serial No. 415,699. Term of patent 7 years.

To all whom it may concern:

Be it known that I, FREDERICK W. WALKER, a citizen of the United States, residing at Royal Oak, in the county of Oakland and State of Michigan, have invented a new, original, and ornamental Design for a Handle, of which the following is a specification, reference being had to the accompanying drawing, forming a part thereof.

Fig. 1 is a side elevation of a handle showing my new design; and

Fig. 2 is a top plan view thereof.

I claim:

The ornamental design for a handle or similar device, as shown.

FREDERICK W. WALKER.
